UNITED STATES PATENT OFFICE.

EUGENE L. KEYES, OF BOSTON, MASSACHUSETTS, ASSIGNOR TO UNITED SHOE MACHINERY COMPANY, OF PATERSON, NEW JERSEY, A CORPORATION OF NEW JERSEY.

APPARATUS FOR USE IN LASTING TOES.

1,143,971.

Specification of Letters Patent. Patented June 22, 1915.

Application filed April 28, 1911. Serial No. 623,874.

To all whom it may concern:

Be it known that I, EUGENE L. KEYES, a citizen of the United States, residing at Boston, in the county of Suffolk and State 5 of Massachusetts, have invented certain Improvements in Apparatus for Use in Lasting Toes, of which the following description, in connection with the accompanying drawings is a specification, like reference characters on the drawings indicating like parts in 10 the several figures.

This invention relates to lasting apparatus and particularly to apparatus designed for use by a hand workman to facilitate the 15 lasting and fastening of the toe portion of a shoe.

This invention is particularly useful in the manufacture of turn shoes, although it is capable of use also in making welt shoes.

20 The object of the invention is to provide means to assist the operator in binding the toe portion of the shoe in lasted position.

An important feature of the invention consists in means constructed and arranged 25 for use by a hand laster for holding a toe binding wire under tension in position to bind the upper in lasted position as the lasting operation proceeds about the toe. This is shown as embodied in a wire guiding arm 30 mounted for movement of its wire delivering end around the toe portion of a shoe from one side of the shoe to the other as the toe of the shoe is being progressively lasted, and means to cause said wiring arm to hold 35 the wire under tension at different points in the path.

Other features of the invention, including certain details of construction and combinations of parts will appear in connection 40 with the following description of an illustrated embodiment of the invention and will then be pointed out in the claims.

Figure 1 is a side elevation; Fig. 2 is a perspective view showing the toe portion of 45 the shoe during the progress of the lasting on the first side of the toe; Fig. 3 is a perspective view showing the toe portion of the shoe during the progress of the lasting on the second side and illustrating in dotted 50 lines the movement of the wire guide for wrapping the wire around the anchor tacks.

The illustrated apparatus comprises a lasting jack having a base to rest upon the floor, a column 2 tubular at its upper end to 55 receive in vertically adjusted position a stem

4 on the upper end of which is formed a circular disk shaped head 5. On a bracket 6 is a similar disk shaped member which is clamped frictionally upon the member 5 by a screw upon which is a wing nut 7. On the left hand end of the bracket 6 is a bearing for a sleeve stem of the jack base 8, said stem having on its lower end a ratchet 10 with which co-operates a locking pawl, not shown, to restrain the jack from rotation or 60 to hold it against rotation in one direction. From one side of the jack base 8 projects a curved horn 14 upon which is adjustably held the sleeved lower end of the toe post 15. Upon an oppositely projecting horn 16 of the 70 base is pivoted a heel post member 18 having a last pin 20 and having a forwardly directed arm pulled upon by a spring 22 that extends into the stem of the base. The spring holds the last pin tipped forwardly 75 and when the shoe is on the last holds the toe portion of the shoe firmly down upon the toe post 15. The column 2 has bearing in a bracket 24 that is adapted to be fastened to a work bench 25.

80 The column 2 is embraced by a split sleeve on the lower end of a bracket 30 which is frictionally clamped thereon to resist turning movement by a screw having an operating handle 32, said arm resting down upon a collar 33 which is adjustable on the column 2 to vary the height of bracket 30. The bracket trends upwardly and at its free end has a horizontally projecting portion to 85 which is clamped in horizontally adjusted position a foot 35 having a slot through which the adjusting bolts 34 extend into the bracket. The foot 35 has a vertical bearing for the lower end of a post 36, said post having a collar 38 to rest on the foot and 90 the foot having a handled bolt 39 by which to hold the post 36 frictionally in the position to which it may be turned in the use 95 of the apparatus. At the upper end of the post is mounted the wiring arm 40, the connection providing for a turning movement of the wiring arm up and down and for frictionally holding said arm in adjusted position. The arm comprises a sleeve member 100 which is directly connected to the post and a rod member sliding endwise in the sleeve member and having a stud 42 in a slot in the sleeve member to limit the sliding movement and to restrain the parts from relative turning movement. A spring 41 holds 105

110

the rod member normally within the sleeve member. The rod member has a tapering nozzle-like free end and a wire passage leading from its end backwardly to a point near the sleeve member. The post 36 supports by 5 a sleeve the spool holder or reel 45 and a tension device 46 through which the wire passes from the spool upwardly into the passage of the wiring arm and thence out from 10 the tapering nozzle.

It will be noted that the connection of the wiring arm to the post is a frictional joint and that the post turns in the foot 35 against a friction determined by the handle 36 and 15 again the bracket 30 turns on the column 2 against a frictional resistance. This provides a flexible supporting means for the wiring arm adapted to permit the arm to be positioned as required in the wiring operation 20 and to maintain the arm in any position to which it is moved. In the use of the apparatus a shoe is applied to the last pin 20 and held in position upon the toe post 15 by the action of the spring 22. The shoe may 25 be pulled over and the sides and the heel seat lasted after having been applied to the jack or the shoe may be prepared for the toe lasting operation in any other desired manner. In beginning the toe lasting operation 30 the workman swings the wiring arm downwardly to the shoe and anchors the free end of the wire to a tack in the right hand side of the shoe. He then swings the wiring apparatus to position the wiring arm about 35 as shown in Fig. 2 with the wire under tension between the tack and the end of the wiring arm and pressing against the upper along the side of the toe. The friction joints in the apparatus may be adequate to hold 40 the wiring arm with the wire under sufficient tension in this position or the tension may be supplemented or maintained by the left hand of the workman on the wiring arm. The workman now with his hand 45 pincers or other lasting devices pulls the upper into lasted position and crimps or plaits it, beginning preferably at the end of the toe and working backwardly along the right hand side and causing the wire to bind 50 the upper with sufficient force to hold it in its lasted position as the operation proceeds from the end of the toe toward the anchor tack. When the lasting of this side of the toe is completed the workman turns the jack 55 about the axis of the post 4 and he turns the wiring apparatus about the axis of the column 2 as may be necessary to cause the shoe and the wiring arm to move progressively from the relative position shown in Fig. 2 60 to the relative position shown in Fig. 3, meanwhile lasting the end and the left hand side of the toe and laying his plaits toward the toe on the left hand side like the plaits were laid toward the toe on the right hand side. With his hand the workman then

hooks the wire over a tack on the left hand side and manipulates the wiring arm to wrap the wire around the tack and secure it. If the workman be left handed the shoe support and the wiring apparatus may be 70 both turned about the axis of the column 2 into a position at the right hand side of that column in the drawings and then the lasting operation will begin with the left hand side of the shoe and proceed around the toe to the 75 opposite side.

That improvement in methods of making shoes herein disclosed is not claimed in this application but constitutes the subject-matter of a divisional application, Ser. No. 80 870,811, filed Nov. 7, 1914.

Having explained the nature of this invention and described a preferred construction embodying the same, I claim as new and desire to secure by Letters Patent of the 85 United States:

1. A lasting apparatus comprising a shoe support, a wire guiding arm mounted for manual movement of its wire delivering end around the toe portion of the shoe from one 90 side thereof to the other by the operator step by step as the lasting proceeds, and means for causing said wiring arm to hold the wire under tension at different points in its path.

2. A lasting apparatus comprising a support for a shoe, a wiring arm, supporting means for the arm permitting movement thereof about horizontal and vertical axes to enable the wiring arm to be manipulated for placing the wire around the shoe toe under 100 tension and friction means for maintaining the wiring arm stationary with the wire under tension at any point to which the arm is moved by the operator.

3. A lasting apparatus having, in combination, a support for a shoe, a wire guiding arm having a wire passage extending lengthwise through it and mountings for the arm permitting it to be moved from and toward the shoe and to be swung step by step by the 105 operator as the lasting proceeds for carrying the wire around the toe of the shoe from one side to the other as the toe is being progressively lasted.

4. A lasting apparatus having, in combination, a shoe support, and a wiring arm, said support and arm being mounted to turn about vertical axes which are spaced a substantial distance apart, the axis of the wiring arm being in front of the axis of the 110 shoe support, and adapted to permit manually controlled rotative movement of the shoe and of the wiring arm in laying the wire around the toe from an anchor tack on one side of the shoe to an anchor tack on the 120 other side step by step as the lasting progresses.

5. A lasting apparatus having, in combination, a shoe support mounted for movement to move the shoe about a vertical axis 125

- located in the rear of the toe, and a wiring arm mounted for rotative movement about a vertical axis located in the front of the toe, said parts being arranged to permit 5 manually controlled rotative movement of the shoe and of the wiring arm in laying the wire around the toe from an anchor tack on one side of the shoe to an anchor tack on the other side of the shoe.
- 10 6. An apparatus of the class described having, in combination, a support for a shoe, and an extensible wiring arm pivotally mounted to permit movement of said extensible arm for laying a binding wire from an 15 anchoring tack on one side of the shoe around the toe to an anchoring tack at the other side of the shoe.
7. An apparatus of the class described having, in combination, a support for a 20 shoe, an extensible wiring arm comprising a rod member having a wire passage and a sleeve member into which the rod is movable, a spring for holding the rod member drawn into the sleeve member and a support 25 upon which the wiring arm is movable about a horizontal axis and which is itself movable about a vertical axis.
8. An apparatus of the class described having, in combination, a support for a 30 shoe, a bracket rotatable about the shoe support, a post in said bracket rotatable therein about its own axis, and a wiring arm connected to the post for movement about a horizontal axis and formed in relatively extensible sections.
- 35 9. An apparatus of the class described having, in combination, a support for a shoe upon which the shoe is rotatable to present one side or the other toward a right or a left handed workman alternatively, and 40 toe wiring devices located in front of the shoe support and adapted for rotation into position for use upon a shoe occupying either of said alternative positions.
10. An apparatus of the class described 45 comprising a column, a shoe jack supported at one side of the column, a bracket mounted to swing about the column, a post adapted to turn in the free end of the bracket, a wiring arm pivoted to the post and friction means 50 for restraining free movement of said members at their points of connection with one another for the purpose described.
11. An apparatus of the class described 55 having, in combination, a shoe jack comprising shoe holding means rotatable about an upright axis located in the rear of the toe, a wiring arm constructed and arranged for use in holding under tension a toe binding wire extending from an anchor tack on one 60 side of the shoe in a position to hold upper materials in lasted relation to the sole of the shoe, and means for holding the jack from rotation in the direction of the pull of the wire running from the shoe to the wiring 65 arm.

In testimony whereof I have signed my name to this specification in the presence of two subscribing witnesses.

EUGENE L. KEYES.
